FIG. 1.

BY

Auguste C. E. Rateau

Frank T. Chamber

his ATTORNEY

INVENTOR

UNITED STATES PATENT OFFICE.

AUGUSTE C. E. RATEAU, OF PARIS, FRANCE, ASSIGNOR TO RATEAU BATTU SMOOTH COMPANY, OF NEW YORK, N. Y., A CORPORATION OF NEW YORK.

MULTISTAGE COMPRESSOR.

1,140,065.

Specification of Letters Patent. Patented May 18, 1915.

Application filed April 16, 1914. Serial No. 832,289.

To all whom it may concern:

Be it known that I, AUGUSTE C. E. RATEAU, a citizen of the Republic of France, residing in Paris, in the Republic of France, have 5 invented certain new and useful Improvements in Multistage Compressors, of which the following is a true and exact description, reference being had to the accompanying drawings, which form a part thereof.

10 This invention consists in an effective arrangement for compressing air, gases or vapor by means of a rotary compressor and a reciprocating compressor working in series, and operated respectively by a steam turbine and a reciprocating engine preferably also working in series. This arrangement is characterized by the fact that the final pressure of the compressed fluid; namely, that at the outlet of the reciprocating compressor, regulates the admission of steam to the turbine in such manner that as the final pressure tends to diminish, the work of the turbine is increased; and the reciprocating compressor, without varying appreciably the work of the steam engine driving it, thereupon discharges a greater quantity of fluid, and reestablishes the final pressure, which is thus maintained approximately constant.

15 The various features of novelty characterizing my invention are pointed out with particularity in the claims annexed to and forming a part of this specification. For a better understanding of the invention, however, and of the advantages possessed by it, reference should be had to the accompanying drawings and descriptive matter in which I have illustrated and described forms in which my invention may be embodied.

20 Of the drawings: Figure 1 is a diagrammatic view of an arrangement in which a low pressure turbine is employed; Fig. 2 is a diagrammatic view of a portion of a modification of the arrangement shown in Fig. 1, in which a regulated escape of exhaust steam from the engine directly to the condenser is permitted; and Fig. 3 is a view taken similarly to Figs. 1 and 2, illustrating an arrangement in which a mixed flow turbine is employed.

25 As shown in the drawings, a reciprocating engine A is connected to a reciprocating compressor B, and a steam turbine D to a rotary compressor E. The connection be-

tween the steam engine and reciprocating engine, on one hand, and between the turbine and the rotary compressor on the other hand, is generally a direct connection in each case, as shown, but it will be understood that a mechanical transmission, or even an electrical transmission, may be employed between each compressor and its driving motor.

30 S is the air inlet of the rotary compressor E, and F the air outlet which is connected to the inlet of the reciprocating compressor B.

35 The pipe G leads from the outlet of the compressor B to the apparatus which utilizes the air or gas compressed. To the conduit G is connected a regulating device H, which is responsive to the pressure of the fluid in the pipe G, and, as illustrated, comprises a cylinder and a piston I working therein. One face of the piston I is subjected to the 40 pressure of conduit G and the other to a pressure which is approximately constant, such as atmospheric pressure. This last pressure may be modified or augmented by a counter-weight, or like means. As shown, a 45 spring J is employed for this purpose. The piston I is connected to the inlet admission valve L of the turbine D by a lever K having the fixed fulcrum T.

50 The operation is as follows: If the pressure lowers in duct G, that is to say, if the demand for the fluid compressed increases, the piston I comes down and increases the admission of steam to turbine D. This increases the speed of the turbine and the 55 work done by the latter. The rotary compressor E then takes in a larger volume of gas, and compresses it to a higher pressure, and the reciprocating compressor B, receiving 60 fluid at this higher pressure, discharges a larger quantity of compressed fluid, and thus reestablishes the normal pressure in the pipe G. As the turbine load thus changes, the work done by the reciprocating compressor does not appreciably vary, for, while 65 its discharging volume is increased on the one hand, the ratio of compression is decreased on the other hand. When the pressure tends to increase in discharge duct G, the regulating operation is the reverse of 70 that just described.

75 As shown in Fig. 1, the turbine D is a low pressure machine and its only source of steam is the exhaust steam from the steam engine A through the conduit C. The tur- 80

bine exhausts to condenser M. Under these conditions, the low pressure turbine is so designed as to absorb all the steam discharged by the reciprocating engine working at maximum power. Under the condition in which the two machines should operate at reduced output the turbine, with the regulation described above, reduces its speed, and delivery pressure, and its steam admission pressure will also diminish.

In order to reduce the steam consumption of the piston engine, it is advantageous to diminish its back exhaust pressure. For this purpose the regulating means already described is combined with regulating apparatus of the kind described in French Patent No. 386,039, January 8th, 1908. This apparatus includes means responsive to the pressure differential at the inlet and outlet sides of the admission valve of the turbine, employed in regulating the discharge of exhaust steam from the reciprocating engine direct to the condenser. In the apparatus of this type shown in Fig. 2, the piston N, which is subjected on the one side through pipe O to the pressure at the inlet side of the throttle valve L, and on the other side to the pressure of a spring R, and to the pressure at the outlet side of the valve L through the pipe P, controls a valve Q. The latter controls an escape conduit leading directly from the pipe C to the condenser M. The valve Q opens and closes as the differential of the pressures at the opposite sides of the valve L increases and diminishes. In this way the pressure of the reciprocating engine is reduced for light loads.

If it is desirable to overload the turbine, the latter can be of the mixed pressure type, and in this case is equipped with a mixed flow regulator, responsive both to the turbine speed and to the pressure in conduit C. Apparatus of this kind is shown in Fig. 3, wherein the mixed pressure turbine DD, replacing the turbine D of Fig. 1, may receive exhaust steam from the reciprocating engine A through the pipe CC and may receive live steam through the pipe U. The flow of steam through the pipes CC and U is controlled by throttle valves C¹⁰ and U¹⁰. These valves are controlled by governing mechanism including a cylinder V to which the pressure in the pipe CC at the inlet side of valve C¹⁰ is transmitted through a pipe V' and including also adjustable connections between the piston V² working in cylinder V and the valves C¹⁰ and U¹⁰, being similar in these respects to the governing mechanism shown in my prior Patent No. 839,318, granted December 25th, 1906. In the present arrangement, however, the link W, through which the connections between piston V² and valves C¹⁰ and U¹⁰ are adjusted, is not connected to and operated by a speed governor, but by the piston I of the device H,

which acts on this regulating device, instead of acting directly on the inlet valve L of Fig. 1. For light loads the turbine DD receives steam only from the low pressure source through pipe C¹⁰. The back pressure on the reciprocating engine is regulated as in Fig. 2 by piston N, which is subjected to the differential of the pressures on the opposite sides of the low pressure throttle valve. The turbine can also be a high pressure turbine and entirely independent of the piston engine, the piston engine exhausting directly into the condenser or to atmosphere. The regulating apparatus H acts then on high pressure inlet valve independently. Essentially this result is secured with the apparatus shown in Fig. 3, when the stop valve C⁵ in the pipe CC is closed.

My invention is obviously adapted for use where the turbine, and the piston engine and the compressors are each in several parts, working in series or in parallel. For example, the reciprocating engine may be compound, or the rotary compressor include two wheel units which compress, in succession, the elastic fluid. This invention is especially applicable to work in mines, but is generally useful in all kinds of installations in which air and gas are compressed.

Having now described my invention, what I claim as new and desire to secure by Letters Patent, is:

1. Apparatus for compressing air or other gases comprising in combination, a rotary compressor, a piston compressor receiving and further compressing the fluid compressed and discharged by the rotary compressor, a steam turbine driving the rotary compressor, a separate motor driving the reciprocating compressor, and means responsive to the delivery pressure of the reciprocating compressor for regulating the admission of steam to the turbine.

2. Apparatus for compressing air or other gases comprising in combination, a rotary compressor, a piston compressor receiving and further compressing the fluid compressed and discharged by the rotary compressor, a reciprocating steam engine driving the reciprocating compressor, a turbine utilizing exhaust steam from said engine and driving said rotary compressor and means responsive to the delivery pressure of the reciprocating compressor for regulating the admission of steam to the turbine.

3. Apparatus for compressing air and other gases comprising in combination, a rotary compressor, a piston compressor receiving and further compressing the fluid compressed and discharged by the rotary compressor, a steam turbine adapted to utilize exhaust steam and driving said rotary compressor, a reciprocating engine driving said piston compressor, a conduit through which exhaust steam from the reciprocating engine

- passes to the turbine inlet, means responsive to the delivery pressure of the reciprocating compressor for regulating the admission of steam from said conduit to said turbine, a condenser and means responsive to the difference between the pressure in said conduit and in the turbine for regulating the passage of steam from said conduit to said condenser.
4. Apparatus for compressing air and other gases comprising in combination, a rotary compressor, a piston compressor receiving and further compressing the fluid compressed and discharged by the rotary compressor, a steam turbine adapted to utilize the exhaust steam and driving said rotary compressor, a reciprocating engine driving said piston compressor, a condenser, and means responsive to the delivery pressure of the reciprocating compressor for governing the passage of exhaust steam from the reciprocating engine to, and its distribution between said turbine and condenser.
5. Apparatus for compressing air or other gases comprising in combination, a rotary compressor, a piston compressor receiving and further compressing the fluid compressed and discharged by the rotary compressor, a reciprocating engine driving said piston compressor, a mixed pressure turbine
- driving said rotary compressor, and governing mechanism for said turbine responsive to the delivery pressure of the reciprocating compressor.
6. Apparatus for compressing air or other gases comprising in combination, a rotary compressor, a piston compressor receiving and further compressing the fluid compressed and discharged by the rotary compressor, a reciprocating engine driving said piston compressor, a mixed pressure turbine driving said rotary compressor, a condenser, valved connections for passing exhaust steam from the reciprocating engine to said turbine and also directly to said condenser, a valved live steam connection to said turbine, and means, responsive to the delivery pressure of the reciprocating compressor, for controlling said valved connections in such manner that at light loads the exhaust steam from the reciprocating engine will pass in varying amounts depending on the load to said condenser and turbine and the latter will be operated exclusively by said low pressure steam, while at larger loads the turbine will receive live steam.
